Attorney

UNITED STATES PATENT OFFICE.

NELSON J. TUBBS, OF LOUISVILLE, KENTUCKY, ASSIGNOR OF ONE-HALF
TO W. O. BRADLEY, OF LOUISVILLE, KENTUCKY.

OVERHEAD OILER.

No. 828,907.

Specification of Letters Patent.

Patented Aug. 21, 1906.

Application filed September 11, 1905. Serial No. 277,970.

To all whom it may concern:

Be it known that I, NELSON J. TUBBS, a citizen of the United States, residing at Louisville, in the county of Jefferson and State of Kentucky, have invented certain new and useful Improvements in Overhead Oilers; and I do declare the following to be a full, clear, and exact description of the invention, such as will enable others skilled in the art to which it appertains to make and use the same.

This invention relates to overhead oiling-cans; and one of the objects of the same is to improve oil-cans of this character by providing means for ejecting oil from a discharge-tube at a point at a distance above the floor.

Another object is to provide an oil-can with a pump and valves which will force a quantity of oil from the reservoir into the discharge-tube at each alternate reciprocation of the pump-piston to force said oil up through an outer discharge-tube into an oil-cup or oil-hole in machinery far beyond the ordinary reach of an oiler.

These and other objects are attained by means of the construction illustrated in the accompanying drawings, in which—

Figure 1 is a perspective view of an overhead oiler made in accordance with my invention, and Fig. 2 is a vertical sectional view of the same.

Referring to the drawings for a more particular description of my invention, the numeral 1 designates the reservoir or container for the lubricant. Secured centrally within said reservoir is a tube or cylinder 2, at the lower end of which a valve-seat 3 is secured. Small openings 4 communicate with the reservoir 1 through the wall of said valve-seat. A gage 5, having its vertical members secured to the valve-seat, serves to limit the movement of a ball-valve 6, said ball-valve adapted to fall by gravity upon the seat. In one wall of the tube or cylinder is a valve-seat 7, adapted to be closed by a ball-valve 8. The ball-valve is placed within a fitting 9, secured at the side of the cylinder in an inclined position, and a spring 10 bears at one side against the ball-valve and at its other end against a tubular elbow 11, extending out through the side wall of the reservoir or oil-container and having secured thereto a telescopic discharge-tube 12. This discharge-tube is provided with a projection 13 near its

hook-point for the purpose of opening the 55 lids of the oil-cups, while the curved terminal end 13 of the discharge-tube is placed within the cup. The telescoping sections of the discharge-tube may be extended or shortened to reach the required cup for replenishing the 60 same. A pump or piston designed to operate within the cylinder comprises a rod 15, having a leather cup 16 upon its lower end and a reversely-disposed leather cup 17 near its upper end, said leather cups being secured 65 in place by means of a tube 18, surrounding the rod 15, washer 19, and nut 20, as shown in Fig. 2. Connected to the upper end of the rod 15 is a pitman 21, the upper end of which is connected to an elbow-lever consisting of 70 two members 22, pivoted at 23 upon a pair of brackets 24, secured to a plate 25, extending laterally at the top of the reservoir 1. The upper ends of said lever are connected by a handle 26, and the spring 27 is secured to a 75 cross-bar 28, said spring extending down and having its free end bearing against the rigid portion of the casing in order to return the pitman or pump-rod to its upper position. A handle 29 is also secured to the upper end 80 of the oil-can, and a filling-orifice 30 of usual construction is disposed between the two members of said handle. A small pipe 31 connects the oil-reservoir with the discharge-tube, and in said pipe is a cock 32. The pur- 85 pose of this construction is to permit oil to return to the oil-reservoir when the oiler has been used.

The operation of my invention may be described as follows: The operator having ad- 90 justed the discharge-tube by extending it to a required degree, takes the can by the handle 29 and pulls the handle 26 toward said handle 29, thus operating the pump by the downward movement of the leather cups. 95 This movement forces oil up above the ball 6, out through the valve-seat of valve 8, and up through the discharge-tube. When the handle 26 is released, the spring 27 throws said handle outwardly and raises the pump-rod. 100 This action lifts the valve from its seat and draws oil through the opening below the valve up within the cylinder. The reverse or downward movement of the pump-valves forces the ball 8 from its seat and the oil out 105 through the discharge-tube. When the oil-can has been used, the discharge-tube can be telescoped within a small space, and the oil

remaining in the lower portion of the discharge-tube can be run back into the reservoir by means of the cock 32.

From the foregoing it will be obvious that my overhead oiler is of comparatively simple construction, is reliable and efficient in use, and for oiling cups or machinery at a distance overhead is very convenient and desirable.

10 Various changes in the form, proportion, and the minor details of construction may be resorted to without departing from the principle or sacrificing any of the advantages of this invention.

15 Having thus described my invention, what I claim as new, and desire to secure by Letters Patent, is—

1. In an overhead oiler, an oil-reservoir, a cylinder within said reservoir, a pump within said cylinder, an elbow-lever for operating said pump, a spring for returning said elbow-lever, a ball-valve at the bottom of the cylinder, a fitting secured to the cylinder, a ball-

25 valve in the fitting and adapted to be forced from its seat by the pump, and a discharge-tube connected to said fitting, substantially as described.

2. In an oiler, an oil-reservoir, a cylinder within said reservoir, a piston within said cylinder, a telescopic discharge-tube, a compound valve adapted to alternately open and close at the movement of the piston to draw a quantity of oil from the reservoir and force the same out through the discharge-tube, a handle, an elbow-lever for operating the piston, and a spring for returning the elbow-lever to its normal position, substantially as described.

30 In testimony whereof I have hereunto set my hand in presence of two subscribing witnesses.

NELSON J. TUBBS.
